UNITED STATES PATENT OFFICE.

WILLIAM A. SARGENT, OF DES MOINES, IOWA, ASSIGNOR OF ONE-HALF TO
JACKSON WISEHART, OF SAME PLACE.

FORCE-PUMP.

SPECIFICATION forming part of Letters Patent No. 240,771, dated April 26, 1881.

Application filed December 9, 1880. (No model.)

To all whom it may concern:

Be it known that I, WILLIAM A. SARGENT, a citizen of the United States, residing at Des Moines, in the county of Polk and State of Iowa, have invented new and useful Improvements in Force-Pumps, of which the following is a specification.

My invention relates to double-acting hand force-pumps, its object being to simplify and render efficient and durable pumps of this class; and it consists in certain novel features of construction, which will be hereinafter fully described, and pointed out in the claim hereto appended.

15 In the accompanying drawings, Figure 1 is a side elevation, and Fig. 2 is a vertical section, of a pump constructed according to my invention. Fig. 3 is a detached view of one of the gaskets and valve-leathers.

20 The letter A indicates the pump-barrel, cast with seats B, having ears or lugs B', by which the barrel may be bolted to the hollow pump-stock C, and having top and base plates, D and E, provided with ears d and e, and secured in place by tension-rods F and nuts f.

25 G is a suction-pipe leading from a point near the top of the pump-barrel, and terminating in an enlarged portion, G', about on a level with the base of said barrel, said enlarged portion having a base-plate, H, provided with ears h, and secured in place by bolts passing through said ears and lugs cast on the enlargement. The base-plates E and H of the barrel and suction-pipe have flanges or rims e' and h', which 35 fit around the peripheral edges of said barrel and the enlarged portion of the suction-pipe, respectively.

Between the end edge of the barrel and its base-plate is arranged the margin of a leather 40 gasket, I, which is formed in one piece with the valve-leather K, the two being composed of a circular leather disk, nearly encircling a central portion of which is cut a narrow segmental aperture, which serves to detach the 45 valve-leather from the surrounding portion, except for a short distance, the part l between the terminals of the segmental cut serving as a hinge for said valve-leather, as shown in Fig. 3.

M is the valve, which may be made of any 50 suitable material, having sufficient weight to hold it well upon its seat, which is the inner face of the base-plate, around a central opening, m, of said plate. From the top of the valve rises a curved spring, N, which extends 55 toward and terminates at a suitable distance from the inner surface of the barrel.

Through the wall of the barrel, near its top and bottom, are formed ports o o', which pass through the centers of the seats B B. 60

Between the edge of the enlargement of the suction-pipe and its base-plate is a gasket, I', having the valve-leather K' formed in one piece therewith, and carrying a valve, M', provided with a curved spring, N', all identical in 65 construction with those just described at the bottom of the barrel.

C is the hollow pump-stock, provided with a spout, c. Through the wall of the stock are formed passages p p', leading to its bore, these 70 passages being the same distance apart as the ports o o' of the barrel, and coinciding concentrically with said ports when the barrel is secured to the stock, as shown in Fig. 2, the passages p p' being considerably larger in diameter than the ports o o'. 75

Between the seats B B and the outer surface of the stock are arranged gaskets I² and I³, each formed in one piece with a valve-leather, K² and K³, carrying valves M² and M³, provided 80 with a spring, N² and N³, all similar to those described for the barrel and suction-pipe, except that the valves M² and M³ are hung vertically and open upward, their springs striking the walls of the passages p p'. 85

The letter Q designates the piston or plunger, which works in the barrel and may be packed in any ordinary manner.

R is the piston-rod, which passes through a central aperture in the top plate, and is connected with the lower end of a pitman, R', the upper end of which is connected to a crank, S, secured to the end of a shaft, T, which has its bearings in the upper portion of the pump-stock, and is provided with a winch, U. 90 95

When, by turning the shaft S, the piston is raised, a vacuum is produced below the piston Q, the valve M is raised, and water flows into

the barrel, the spring N striking the wall of the barrel after the valve rises some distance, and being somewhat compressed during the time the valve is raised; but immediately the 5 direction of the piston is reversed the valve is relieved of the upward pressure of the water and its spring suddenly reacts, causing the valve to promptly resume its seat. The spring offers no resistance to the initial rising of the 10 valve, and is only compressed when the water has attained a considerable momentum. Said spring does not in the least oppose the suction. At the same time the valve M² is forced back, opening the port o and permitting the water 15 to flow to the bore of the stock. The descent of the piston causes the vacuum about and in the suction-pipe, so that the valve M' at the bottom of said pipe is raised, and water flows through the pipe to the upper portion of the 20 barrel, the valve M' remaining closed until the piston again moves upward, when it is forced back and permits the water above the piston to flow to the stock. As soon as the water-pressure upon any one of the valves ceases it 25 is thrown back promptly to its seat by the action of its spring.

Heretofore a pump has been constructed of a stationary discharge-pipe connected with a cylinder by two pipes, one entering the cylinder at the top and the other at the bottom, a 30 supplemental pipe being connected with the top of the cylinder and its lower end being

open to the water, as in United States Patent No. 193,689. A force-pump has also been constructed of an ordinary pump-stock having 35 lateral ports communicating with a cylinder detachably connected with one side of the pump-stock, as in United States Patent No. 184,613, and as the structures shown and described in these patents are not my invention, 40 they are hereby disclaimed.

What I claim is—

The combination, with the pump-stock C, having the lateral passages p p', of the pump-barrel A, detachably connected with one side 45 of the pump-stock, and provided with the inlet-valve M at its lower end, and the lateral valved ports o o', communicating with the interior of the pump-stock through its lateral passages, the suction-pipe G, leading from the 50 top of the pump-barrel and terminating near the base of the latter in a valved portion, G', and the piston Q, connected with operating devices and arranged to reciprocate between the valved ports o o', all substantially as and for 55 the purpose described.

In testimony whereof I have hereunto set my hand in the presence of two subscribing witnesses.

W. A. SARGENT.
